UNITED STATES PATENT OFFICE.

TILESTON O. THAYER, OF ALCYON, OREGON, ASSIGNOR OF TWO-FIFTHS TO GEORGE E. RIGGS, OF ALCYON, OREGON.

GATE.

Application filed August 17, 1921. Serial No. 493,085.

To all whom it may concern:

Be it known that I, TILESTON O. THAYER, citizen of United States, residing at Albany, in the county of Linn and State of Oregon, have invented certain new and useful Improvements in Gates, of which the following is a specification.

This invention has reference to gates and more particularly to a gate structure embodying means operable from a distance from the gate for opening and closing same.

An additional object is to provide an improved gate structure embodying means operable by a person in a vehicle for opening and closing the gate without compelling said person to alight from the vehicle in which he may be riding.

An additional object is to provide a gate structure of generally improved construction and design and including latch means adaptable to all kinds and makes of gates, said latch means being so intimately associated with the opening and closing means as to be automatically thrown into locking and releasing positions as the gate is swung between the posts.

With the above and other objects in view, the invention may be said to reside generally in the details of construction, combination and arrangement of parts as will be herein-after more fully described, reference being had to the accompanying drawings wherein:

Figure 1, is a perspective view of a gate embodying the invention; Figure 2 a plan view of the invention, partly in section, Figure 3 is a fragmentary detail view of a gate portion, disclosing the pulley or rope guide at the end of the latch bar; Figure 4 is a cross sectional view taken on line 4-4 of Figure 3; and Figure 5 a detailed view of the main ring-catch or detent of the gate post.

Corresponding and like parts are referred to in the following description and indicated in the several views of the drawings by like reference characters.

The device may be constructed of wood, metal or other suitable material and com-

prises a gate 1 mounted to swing about hinge post 2 and co-operating with the gate, 50 latch posts 3 and 4 respectively. Hinges 5 connect the gate with post 2 and permit it to swing freely with its opposite end moving in an arc between posts 3 and 4. Pivoted to the gate, as at 6 is a horizontally disposed latch-bar 7 the long arm of which works in a bracket guide 8 fastened to the gate as shown in Figure 1. This bracket provides a rest or support for the latch-bar and tends to hold the same in a horizontal position. At its outer end the latch bar projects forwardly of the gate as shown at 9 for engagement with the detent on post 3 when the gate is swung into closed position. 60 This detent comprises a ring guide 10, preferably in the form of a metal strap fastened to post 3 and projecting laterally of one side thereof in loop formation to receive therebetween a ring 11. This ring is loosely supported between the arms of the loop 10 by 65 a cross pin 12, the ring normally depending below the loop as shown to advantage in Figure 5 of the drawings. Consequently, 70 when the gate swings closed, the ring is forced upwardly through the loop by the 75 pressure of latch bar end 9 which comes in contact therewith, the ring offering no resistance to the advance of the latch bar. However, when the bar has passed beyond 12 and is adjacent post 3, ring 11 is caused to 80 drop downwardly through the guide, coming between end 9 of the latch bar and the bight 13 of the loop 10, thereby locking the gate in place as the bight of the loop prevents the ring from being lifted upwardly 85 by any attempted backward movement of the latch bar. As will be clearly seen in Figure 5, the pin 12 which supports ring 11 is spaced from the bight 13 less distance than the diameter of the ring 11 so that any 90 tendency of the gate to open after the latch-bar 9 has been positioned between the ring 11 and post 3 will be prevented by the latch-bar 9 engaging against the ring 11 which in turn is prevented from vertical displacement 95 by any outward movement of the latch bar

9, by the outermost portion of the ring 11 abutting the bight 13 of the loop 10. Moreover, when the end of the latch bar 9 is moved downwardly by the operating means 5 to open the gate, it will engage the underside of the ring 11 and move it upwardly a sufficient distance to allow the latch-bar 9 to pass the same thereby permitting the gate to swing to an open position. At its opposite end the latch bar is provided with a rope guide 14, preferably a pulley supported upwardly from the bar by a bracket 15. This guide is adapted to be engaged by a pull rope 16 which passes under the pulley and engages the gate to which it is fastened as shown at 17. The other end of the pull rope is fastened to one end of a centrally pivoted lever arm 18 supported by post 19 and having its lower end connected by a rope 20 to the lower end of a lever 21, corresponding to lever 18 but mounted on the opposite side of the gate and pivoted to post 22. Posts 19 and 22, are preferably out of longitudinal alignment with posts 2 and 4, being spaced therefrom and remotely positioned from the gate on opposite sides. Lever 21 has its upper end connected to the gate by a pull rope 23 as shown.

Post 4 is provided, adjacent its lower end, 20 with a guide bracket 24 and a pivoted gate catch 25 movable in an up and down direction within the bracket, the forward end of the catch being bent to engage over the lower bar of the gate when the latter is swung open against post 4. This movable gate catch is provided with a pulley or rope guide 26 adapted to engage over rope 20 and connected to the catch as shown at 27.

In the operation of the device the gate 40 when closed is normally arranged as shown in Figure 1 of the drawings. The gate is then closing the road of other passage way between posts 2 and 3 and is held latched by ring 11 as previously described. When it is desired to open the gate to permit the 45 passage of a vehicle approaching the same from the side thereof on which the lever 21 is situated and without requiring the person to alight from such vehicle, the upper end of lever 21 is pushed in toward the gate thereby slackening cable 23 and pulling on cable 20 to move the lower end of lever 18 inwardly toward the gate. This movement causes the upper end of lever 18 to move outwardly away from the gate thereby 50 tightening and tending to straighten cable 16 which lifts the rope guide 14 to cause the latch end 9 of the bar 7 to move downwardly and disengage the detent on post 3. After 55 the detent has been disengaged, cable 16 pulls outwardly of the gate away from the approaching team so as to swing the gate forwardly and toward post 4 until the lower cross bar of the gate engages behind latch

25. The gate will then be held in open 65 position while the team draws through.

To close the gate after the team has passed between the gate posts 2 and 3, the upper end of lever 18 is grasped and moved toward the post 4 which movement causes a pull on 70 cable 20 to swing the lower end of lever 21 inwardly toward gate post 2 during which time the cable 20 is drawn out straight and elevated to cause elevation of the latch 25 to release the lower cross bar of the gate. 75 The lower end of the lever 21 being moved toward gate post 2 causes the upper end of this lever to move outwardly away from the gate thereby tightening and pulling cable 23 toward post 22, and the connections with the 80 cable 16 and 23 with the gate being arranged about ten inches or so from the hinges, the cable 23 will swing the gate to a closed position so that the free end of the latch bar 7 will pass under ring 11 and hold the gate 85 in a closed position. It will also be understood that the posts 19 and 22 are set in on the road out of line with the posts 2 and 4, or these two posts may be situated to one 90 side of the road just so they are out of alignment with the posts 2 and 4.

When approach toward the gate is made from the side thereof on which post 19 is situated to open the gate it is necessary to move the upper end of lever 18 outwardly 95 and in the direction from which the team is approaching so as to cause cable 16 to act upon the latch and gate in the same manner as it acted upon these elements when the upper end of lever 21 was moved toward the 100 gate post 2 as described hereinbefore. It will thus be seen that the invention includes a gate structure having gate opening means of practical operation and designed to permit the opening and closing of a gate without requiring a person to alight from a vehicle in which said person or persons may be riding.

The foregoing description and accompanying drawings have reference to what 110 might be considered to be the approved or preferred form of my invention. I desire it to be understood, however, that I may make such changes in the construction combination and arrangement of parts, materials, and dimensions as may prove expedient and fall within the scope of the appended claim.

Having thus described my invention, what 115 I claim as new and desire to secure by Letters Patent is:

In combination with a gate, a post, a detent comprising a vertically movable ring normally arranged in its lowermost position, 120 said ring being restricted in its movement outwardly of said post, a latch bar fulcrumed on the gate and having one end normally urged upwardly for cooperation with

the ring and adapted to engage the bottom of the ring to raise the same whereby the said end of the latch bar can be retained between the ring and the post when the gate

5 is closed, and said detent engaging end of said bar being movable downwardly to engage the bottom of the ring to raise the same when the bar is operated to open the gate, said ring being immovable when its side

adjacent the post is engaged by said latch 10 bar.

In testimony whereof I affix my signature in presence of two witnesses.

TILESTON O. THAYER.
